UNITED STATES PATENT OFFICE.

HARRY W. PFEIL, OF CHICAGO, ILLINOIS.

STOVE-BOAED.

1,192,931.

Specification of Letters Patent.

Patented Aug. 1, 1916.

Application filed November 29, 1915. Serial No. 63,938.

To all whom it may concern:

Be it known that I, HARRY W. PFEIL, a citizen of the United States, residing at 3960 Broadway, in the city of Chicago, county of 5 Cook, and State of Illinois, have invented certain new and useful Improvements in Stove-Boards, of which the following is a specification.

My invention relates to improvements in 10 boards upon which stoves or like articles may be mounted and more particularly to devices of this character which are constructed of light and fire proofed material.

The objects of my invention are to produce 15 an efficient, very cheap and exceedingly simple device of wood or other similar material and to so cover and coat the top surface and edges of the material of the device that it is rendered practically fire and moisture 20 proof and also provided with a durable finish of pleasing and polished appearance.

These and other objects I accomplish as 25 hereinafter set forth in the following description and as more particularly pointed 30 out in the appended claim, reference being had to the accompanying drawings in which an embodiment of my improvement is illustrated.

In the drawings, Figure 1, is a top plan 35 view of my improved device, sections being broken away at one corner thereof to show the various layers forming the composite board. Fig. 2, is a transverse section through the board on line 2—2, Fig. 1.

In referring to the embodiment of my invention shown in the accompanying drawings in detail, like numerals designate corresponding parts.

My improved board as shown comprises 40 an intermediate layer 1, and two other layers 2 and 3, between which the intermediate layer is interposed and firmly cemented, the thin layers being superimposed upon each other to form a flat strong composite 45 board of considerable thickness.

The thin layers preferably are left rough surfaced just as they come from the saw, not being planed, smoothed or finished in any way, thus considerably lessening the 50 cost of manufacture and providing a fairly rough surface for the cement.

I prefer to make the intermediate layer 1, of fairly soft wood and about three times as thick as the outer layers and to arrange it 55 so that its grain is about at right angles to

the outer layers to prevent warping or splitting.

The outer layers 2 and 3 are preferably of harder wood and are perhaps made thin enough to be termed veneers.

To protect the composite board from the stove or other articles mounted upon it, I cover the top surface and side edges of the same with a thick coat of fire proof composition. In fact in some instances and for 60 some purposes I may cover both the top and bottom surfaces with the fire proof coating but for ordinary use the bottom is protected sufficiently by the floor upon which it is placed. The composition employed by me 65 preferably consists of the following ingredients mixed in approximately the proportions stated: plaster of Paris, 25 per cent.; fireproof cement, 35 per cent.; asbestos, 25 per cent.; shellac, 15 per cent. These 70 ingredients are mixed to about the consistency of a fairly thick paint and then applied to the surface of the board in any suitable manner. A fairly thick coat is preferable 75 as it provides a better and more durable protection. After the board is covered it is placed where the covering can set and dry. Any suitable fire proof paint may also be 80 included in the composition in order that a finished surface of any desired color may be 85 produced.

As shown in Fig. 2 of the accompanying drawings, the thick coating 4, of fire proof composition is spread evenly over the top surface of the board and is also placed upon the edges as indicated at 5, thus protecting 90 both the top and exposed edges from fire and also from moisture.

My improved board can be used for a variety of purposes but is principally adapted to be placed beneath a stove.

While I have illustrated and described a preferred form of construction for carrying my invention into effect this is capable of a wide range of variation, alteration, modification and change without departing from the spirit of my invention. I therefore do not wish to be limited to the construction herein shown and described, but desire to avail myself of all such variations, alterations, modifications and changes as fairly fall within the scope of the appended claim or may be construed to be within the scope thereof by involving the doctrine of equivalents.

What I claim as my invention and desire to secure by Letters Patent is:—

A board of the class described, comprising an intermediate layer of fairly thick soft wood, two thin layers of harder wood between which the intermediate layer is interposed, said intermediate layer having its grain at an angle to the grain of the thin

layers, and a heavy covering of fire-proof composition upon the exposed top and edge 10 surfaces of the board.

Chicago, Illinois, November 24th, A. D. 1915.

In testimony whereof I have this day set my hand.

HARRY W. PFEIL.
